DESIGN FOR A HANDBAG OR THE LIKE

Gerald Murphy, New York, N. Y., assignor to
Mark Cross Company, New York, N. Y., a corporation of New York

Application March 26, 1948, Serial No. 145,385

Term of patent 14 years

(Cl. D87—3)

To all whom it may concern:

Be it known that I, Gerald Murphy, a citizen of the United States, residing at New York, in the county and State of New York, have invented a new, original, and ornamental Design for a Handbag or the like, of which the following is a specification, reference being had to the accompanying drawing, forming part thereof.

Fig. 1 is a perspective front view of a handbag embodying my new design, in closed position;

Fig. 2 is a view of the same in opened position; and

Fig. 3 is a perspective rear view of the handbag in closed position.

The dominant features of my design reside in the portion shown in full lines.

I claim:

The ornamental design for a handbag or the like, substantially as shown and described.

GERALD MURPHY.
